(57) **CLAIM**

The ornamental design for a universal opener and cutting tool, substantially as shown and described.

DESCRIPTION

FIGS. 1–7 illustrate a first embodiment of the invention in which:

FIG. 1 is a rear perspective view showing the first embodiment of the invention;

FIG. 2 is a front perspective view;

FIG. 3 is a first side view;

FIG. 4 is a second side view;

FIG. 5 is a first end view;

FIG. 6 is a second end view;

FIG. 7 illustrates the first embodiment with a cutting utensil extended;

FIGS. 8–14 illustrate a second embodiment of the invention in which:

FIG. 8 is a rear perspective view showing the second embodiment of the invention;

FIG. 9 is a front perspective view;

FIG. 10 is a first side view;

FIG. 11 is a second side view;

FIG. 12 is a first end view;

FIG. 13 is a second end view; and,

FIG. 14 illustrates the second embodiment with a cutting utensil extended.
